UNITED STATES PATENT OFFICE.

LEONA J. CRITCHER, OF CHICAGO, ILLINOIS.

UNDERGARMENT.

No. 828,463.

Specification of Letters Patent.

Patented Aug. 14, 1906.

Application filed November 7, 1905. Serial No. 286,286.

To all whom it may concern:

Be it known that I, LEONA J. CRITCHER, a citizen of the United States, residing at Chicago, in the county of Cook and State of Illinois, have invented a certain new and useful Princess Undergarment, of which the following is a specification, reference being had therein to the accompanying drawings.

This invention relates to undergarments, 10 the object of the invention being to provide a combination undergarment of the style known as "princess," said garment combining several garments in one and being applicable to the body in one operation.

15 Among other objects of the invention this invention aims to provide a neat, graceful, and perfect-fitting undergarment for ladies' use which will hang or drape gracefully upon the figure and be supported effectively from 20 the shoulders without causing any binding on any portion of the body, the novel construction and cut and configuration of the garment adapting the same to thoroughly cover and protect the body and adding 25 greatly to the comfort of the wearer.

With the above and other objects in view the invention consists in a princess undergarment embodying certain novel features and 30 details of construction and relative arrangement of parts, as hereinafter fully described, illustrated, and claimed.

In the accompanying drawings, Figure 1 is 35 a perspective view of the combination undergarment of this invention shown applied to the figure. Fig. 2 is a plan view of the garment spread out and looking toward the inside thereof. Fig. 3 is a plan view of one-half of the garment separated down the middle line of the back, showing the front piece, 40 the under-arm piece, and the back piece, also the arrangement of darts. Fig. 4 is a plan view of one of the back pieces of the drawers-leg. Fig. 5 is a plan view of one of the front pieces. Fig. 6 is a similar view of one of the 45 back pieces.

Like reference-numerals designate corresponding parts in all the figures of the drawings.

The undergarment contemplated in this 50 invention is made up of a number of pieces or widths, as shown in the accompanying drawings, and comprises the two main back pieces 1 1, the front pieces 2 2, and the under-arm pieces 3 3. All of these pieces are cut full 55 length, or, in other words, extend from the

bottom of the garment upward until it is necessary to terminate them at the neck-line or beneath the arm, as the case may be. The back pieces are narrowest at the waist-line, which is indicated at 4, and flare or increase 60 in width from the waist-line downward to the bottom of the skirt and also upward to the extreme top of the garment in order to make the finished garment conform to the lines of the body and fit and hang gracefully upon 65 the body. The under-arm pieces are of corresponding flare and extend from the bottom of the skirt upward to the armhole, the extreme upper edge 5 of the under-arm piece forming a portion of the boundary of the 70 armhole. The front is composed of two similar pieces, each of which is formed with a long vertical dart 6 to provide the necessary contraction at the waist-line, and from the waist-line upward each front piece is gored to 75 the adjacent under-arm piece along the line 7. Each of the front pieces 2 is made of considerable width along the extreme lower portion to form drawers-leg extensions 8, while by reason of the dart 6 a considerable flare is 80 also given to the upper portion of each front piece 2, as shown at 9, to fit around the front upper portion of the body. At a point in line with the waist-line of the garment each front piece 2 is provided with a dart 10, 85 which is formed by cutting the front piece from the front edge inward to the dart 6, removing a portion of the material at such point and stitching the edges together, the effect of which is to draw up the drawers-leg 90 extension 8, and thereby do away with the sagging of such portion of the garment which would necessarily occur were the dart 10 not provided.

It will be understood that the front is gored 95 under the arms to conform to the normal curves and lines of the body. The front of the garment extends to the shoulders and is hollowed down at the front and back, as shown at 11 and 12, and cut out to form the 100 armholes. The back pieces and also the front pieces preferably extend to the shoulders, or, in other words, are provided with extensions 13 and 14, which pass upward over the shoulders and are united at such 105 points to form shoulder-straps; but, if desired, separate straps may be employed and stitched or connected in any suitable manner to said back pieces and front pieces.

In addition to the parts above referred to 110

two back drawers-leg pieces 15 are provided, said pieces being stitched along one edge 16 to the under-arm seam between the front pieces 2 and the under-arm pieces 3. The upper edge of each leg-piece 15 is stitched to the main body of the garment at the waist-line, and the upper edges of the two leg-pieces 15 are made sufficiently wide to overlap, as shown at 17, and the edges 18 are so rounded 5 or curved in an outward direction that such edges 18 overlap to a greater and greater extent as they leave the waist-line until the point is reached where the drawers-leg pieces 15 begin to separate, from which point they 10 diverge. The side edges of the leg-pieces 15 are joined to the corresponding side edges of the extensions 8 of the front pieces 2 along the seam 19, thus completing the structure 15 of the main body of the garment. The edges 20 of the front from the waist-line to the top of the garment are turned back and hemmed, as shown at 20, while from the waist-line downward the edges are faced, as shown at 21, such facing being continued all around the 25 unattached edges of the drawers-leg extensions of the front and the back drawers-leg pieces entirely up to the top of the drawers-leg pieces. This provides projecting front flaps 23, which overlap each other when the 30 garment is adjusted to the person. The seam at each side of the garment between the front piece and under-arm piece is left unstitched for a distance upward from the bottom of the garment, and such unstitched portions of the 35 pieces are rounded, as shown at 22. The drawers-legs extend downward only as far as the bottoms of said side seams. The advantage of this arrangement is that the drawers-legs are prevented from sagging below the 40 bottom of the skirt in the back. Also the openings left in the side seams at the bottom of the skirt allow ample fullness and freedom in walking or sitting.

It will be seen that practically an entire 45 underwear outfit for ladies' use is provided in a single garment and that the same may be worn either under or over the corsets. It will further be seen that the entire garment as a whole is supported directly from and by the 50 shoulders. The garment is adjusted to the body with the same ease and rapidity that a single garment, such as a waist or skirt, could be adjusted. Further, it will be observed that the garment as a whole is open at the 55 front entirely from top to bottom, thereby greatly facilitating the putting on and taking off of the same.

I claim—

1. An open-front princess undergarment 60 embodying a skirt, waist and drawers and comprising front pieces and back pieces extending from top to bottom of the garment, under-arm pieces extending from the bottom of the garment to the armholes, and drawers-

legs consisting of extensions of the front 65 pieces, and other pieces which form the backs of the drawers-legs and are united to said extensions and the body of the garment.

2. An open-front princess undergarment 70 embodying a skirt, waist and drawers and comprising front pieces and back pieces extending from top to bottom of the garment, under-arm pieces extending from the bottom of the garment to the armholes, and drawers-legs consisting of extensions of the front 75 pieces, and other pieces which form the backs of the drawers-legs and are united to said extensions and the body of the garment, the front pieces being provided with up-and-down darts and cross-darts extending from the front edges of the garment laterally to the up-and-down darts.

3. An open-front princess undergarment 85 embodying a skirt, waist and drawers and comprising front pieces and back pieces extending from top to bottom of the garment, under-arm pieces extending from the bottom of the garment to the armholes, and drawers-legs consisting of extensions of the front 90 pieces, and other pieces which form the backs of the drawers-legs and are united to said extensions and the body of the garment, the front pieces being provided with up-and-down darts and cross-darts extending from the front edges of the garment laterally to the up-and-down darts, and the edges of the front 95 from the cross-dart upward being turned back and hemmed, while said front edges from the cross-dart downward are faced and project beyond the hemmed portions to provide an overlap from the waist 100 downward.

4. An open-front princess undergarment 105 embodying a skirt, waist and drawers and comprising front pieces and back pieces extending from top to bottom of the garment, under-arm pieces extending from the bottom of the garment to the armholes, and drawers-legs consisting of extensions of the front 110 pieces, and other pieces which form the backs of the drawers-legs and are united to said extensions and the body of the garment, the front pieces being provided with up-and-down darts and cross-darts extending from the front edge of the garment laterally to the 115 up-and-down darts, and the edges of the front from the cross-dart upward being turned back and hemmed, while said front edges from the cross-dart downward are faced and project beyond the hemmed portions to provide an overlap from the waist 120 downward, and fastening devices located at or near the opposite ends of the cross-darts to secure the overlapping portions.

5. An open-front princess undergarment 125 embodying a skirt, waist and drawers and comprising front pieces and back pieces extending from top to bottom of the garment,

under-arm pieces extending from the bottom of the garment to the armholes, and drawers-legs consisting of extensions of the front pieces, and other pieces which form the backs 5 of the drawers-legs and are united to said extensions and the body of the garment, the bottoms of the seams between the front and under-arm pieces being left open and the portions thereof at each side of the seam being

rounded, while the drawers-legs terminate at 10 the top of said openings.

In testimony whereof I affix my signature in presence of two witnesses.

LEONA J. CRITCHER.
